FOREIGN PATENT DOCUMENTS

EM 008550313-0001 * 5/2021

Primary Examiner — Paula Allen Greene(74) *Attorney, Agent, or Firm* — Renner, Kenner, Tama L. Drenski(57) **CLAIM**

The ornamental design for headphone part, as shown and described.

DESCRIPTION

1. Headphone part

1.1 : Front perspective of a headphone part;

1.2: Left elevation of a headphone part;

1.3: Top elevation of a headphone part;

1.4: Right elevation of a headphone part;

1.5: Bottom elevation of a headphone part; and,

1.6: Top plan view of a headphone part.
